UNITED STATES PATENT OFFICE.

GEORGE F. GRUBE, OF EVANSTON, ILLINOIS, ASSIGNOR TO THE BELBER TRUNK & BAG COMPANY, OF PHILADELPHIA, PENNSYLVANIA, A CORPORATION OF PENNSYLVANIA.

WARDROBE-TRUNK.

1,367,251.

Specification of Letters Patent.

Patented Feb. 1, 1921.

Application filed November 8, 1919. Serial No. 336,572.

To all whom it may concern:

Be it known that I, GEORGE F. GRUBE, a citizen of the United States, residing at Evanston, county of Cook, and State of Illinois, have invented new and useful Improvements in Wardrobe-Trunks, of which the following is a full, clear, and exact description, reference being had to the accompanying drawings, which form a part of this specification.

The object of my invention is to provide a device for use in wardrobe trunks by means of which the garment suspended in the trunk compartment may be held in substantially fixed position therein.

The object of my invention is to provide an efficient and more durable and readily operable retainer or follower which, while utilizing certain known structural features, contains also certain features of novelty.

A preferred embodiment of the invention is shown in the accompanying drawings, in which—

Figure 1 is a perspective view of a wardrobe trunk with my invention applied thereto.

Fig. 2 is a front view of the upper part of a trunk compartment and the upper part of the retainer.

Fig. 3 is a detail view of one of the pair of upper holders for the retainer.

Fig. 4 is a front view of the retainer detached from the trunk.

Fig. 5 is a vertical section on the line 5—5 of Fig. 4.

Fig. 6 is a top view of the trunk compartment containing my invention, with the hinged compartment cover removed.

a and *b* are the two hinged compartments of a trunk, compartment *b* having a hinged top *c*. Compartment *b* is provided with an extensible supporter for garment hangers, this supporter comprising rods *d* secured to the rear wall of the compartment and sleeves *e* in telescopic relation with the respective rods and slidable on brackets *f* projecting inward from the side walls of the compartment. On this supporter is adapted to be suspended any number of garment hangers *g*, which may be of any conventional form. These hangers may be slid back and forth along the supporter and may be individually removed and replaced.

The garment retainer embodies the prin-

ciple of construction of a retainer set forth in my above named pending application, but contains certain improvements and is differently suspended at the top.

h is a metal bar of square contour at the ends and preferably of the same contour throughout its length. Suspended from this bar is a flexible garment protector comprising a front section *x* and a rear section *y*. Each section comprises a facing fabric and a lining of canvas or other stiffening material. The two sections of the protector are secured together along opposite edges from a point just beneath the top suspension bar *h* for a certain distance and are unsecured throughout the remainder of their length. The two sections are also secured together transversely at or near the bottom of the protector.

Extending between sections *x* and *y* and secured to one of them across the fabric at about the level of the junction between the closed and open edges of the protector is a pocket *z* inclosing and supporting a flat metal bar *i*, whose length is about equal to the width of the protector. From this bar is suspended a plurality of coil springs *j* which in turn carry a cross-bar *k*. Like the pocket *z* and bar *i*, the springs *j* and bar *k* are located between the two sections of fabric.

The bars *h* and *k* project laterally beyond the edges of the flexible protector and are adapted to engage holding bars secured to the side walls of the compartment. The lower pair of holding bars, with which the lower cross-bar *k* of the retainer is removably engageable, is of known form and comprises angle bars *m* provided with a succession of angular notches *n* adapted to receive the ends of the rod *k*.

Each holding bar of the upper pair comprises an angle bar *o* along whose upper edge is arranged a series of projections *p*. Each projection has vertical edges and rounded tops, thereby forming between them recesses with parallel vertical walls. Projecting rearward from each projection, at the top of the recess to the rear thereof, is a slightly overhanging shoulder *r*. The width of these recesses, less the depth of the shoulder *r*, is just sufficient to easily accommodate the square ends of the upper or suspension bar *h*. Each bar *h* has end heads

s to prevent lateral slippage and disengagement of the bar h after it is positioned in its holding bars o.

Secured to the top of the bar h are one 5 or more handles made, preferably, in the shape of loops t.

The holding bars h are arranged above the level of the extensible hanger supporter d e and when the retainer is positioned in 10 the trunk the suspension bar h overlies the hanger supporters d e and the garment hangers g.

The retainer is removable from in front of the garments by either swinging up the 15 lid c and raising the suspension bar h by means of the handles t and dropping the retainer down over the front of the hanger supporter, or by pulling down and then forwardly the lower cross-bar k and then either 20 lifting it up over the top of the trunk or lifting the retainer out of the trunk by means of the handle t. The retainer is adjustable both at bottom or top to confine the 25 garments against the rear wall of the compartment.

It will be understood that the invention is 30 equally applicable to the lid compartment of a trunk of the old type, comprising a spacious body resting on its bottom and a lid swinging on the rear upper edge of the body.

Having now fully described my invention, what I claim and desire to protect by Letters Patent is:

35 1. A wardrobe trunk having a compartment, a garment hanger supporter positioned therein, a pair of holding bars at the

upper portion of the compartment, one bar on each side of the compartment, said bars having upwardly extending projections, a 40 second pair of holding bars below the first pair of bars having downward projections, a garment retainer having an upper bar arranged to be seated between the projections on the upper holding bars, a lower bar for 45 the retainer arranged to be seated in the recesses between the projections on the second pair of holding bars, and a flexible connecting member between the upper and lower retainer bars, the upper bar of the 50 garment retainer being above the garment hanger supporter, so that the garment supporting portions of the hangers will be between the upper and lower bars of the retainer, whereby the upper portions of the 55 garments draped on the hangers are compressed by the retainer.

2. A garment retainer for a wardrobe trunk having an upper supporting bar of rectangular cross-section at its support engaging portions, supporting members for each end of said bar having spaced projections, there being recesses formed between said projections having parallel side walls, the bottoms of said recesses being at 60 right angles to the side walls, and a short laterally extending projection on the upper end of each projection overhanging the recess to prevent upward movement of the retainer bar when at that side of the recess. 70

In testimony of which invention I have hereunto set my hand at Chicago, Ill., on this 5th day of November, 1919.

GEORGE F. GRUBE.
